UNITED STATES PATENT OFFICE.

JOHN S. CLARKE, OF DETROIT, MICHIGAN, ASSIGNOR TO HIMSELF AND
JOSEPH FRANK DUNNEBACK, OF SAME PLACE.

FEED-WATER APPARATUS FOR STEAM-BOILERS.

SPECIFICATION forming part of Letters Patent No. 276,354, dated April 24, 1883.

Application filed January 31, 1883. (No model.)

To all whom it may concern:

Be it known that I, JOHN S. CLARKE, of Detroit, in the county of Wayne and State of Michigan, have invented a new and useful Improvement in Feed - Water Apparatus for Steam-Boilers, of which the following is a full, clear, and exact description.

My present invention is an improvement on the feed-water regulator shown in my application for patent filed August 24, 1882, and allowed October 9, 1882.

The first part of my invention relates to means for obtaining uniform pressure, both internally and externally, of the float, and for keeping water from entering the float.

The second part of the invention relates to a relief-valve, which is operated automatically by the main valve, for relieving the pressure when the main or regulating valve is closed.

The third part of the invention relates to means for working an injector or inspirator for feeding the boiler.

Reference is to be had to the accompanying drawings, forming a part of this specification, in which similar letters of reference indicate corresponding parts in all the figures.

Figure 1 is a sectional elevation of my improved apparatus. Fig. 2 is a detail section of the relief-valve. Fig. 3 is a sectional elevation, showing the arrangement of the apparatus for use upon a locomotive or other boiler for starting an injector or pump. Fig. 4 shows the relief-valve separately.

A is the body of the regulator, attached to the boiler at T, substantially as shown in my aforesaid application.

B is the float, and F F the valves of the regulator.

E is the stem or guide of the float, consisting of a tube extending from near the bottom of the float, through the upper part of the boiler, to and within the lower part of the regulator A, so that steam may freely enter the tube and pass to the float, thereby balancing the external pressure. At the same time, by the height of the tube, water is prevented from entering, so that the float is kept dry internally at all times. The float B may be of spherical, elliptic, or other form.

Within the body A of the regulator is fitted a double puppet-valve, a, in connection with an outlet, b, that allows escape of steam when the double valve is raised. The valve a is raised at the upward movement of the main valves F by engagement of the upper valve therewith, so as to let out the steam and immediately relieve the pressure in the pipe running from the regulator. The valves F are shaped, as shown, so that they will first close and then move far enough to open the valve a. The upper valve is slightly larger in area than the lower one, so as to keep the float submerged below its buoyancy-line, and in that way the float is given a constant tendency upward, thereby insuring a more positive action. This also affords the advantage that in case the float should be injured the overpressure on the upper valve would cause the alarm to sound.

At d is the steam-pipe from the regulator for carrying steam to the pump or injector.

At D in Fig. 3 is an injector connected with the water-supply pipe f, and provided with an overflow-pipe, h, that leads to a vessel, i.

k is a piston in the vessel i, connected by a rod, k', with a lever, l, that is arranged for opening and closing the overflow.

m is a valve fitted in the pipe g, that leads from the injector to the boiler, and the stem of the valve passes through the under side of the pipe, and is connected by a lever, n, to the rod k' of the piston k. This arrangement is more especially designed for locomotives, but may be used for stationary boilers and for starting pumps.

The operation is as follows: As soon as the water lowers in the boiler the double valves of the regulator open, allowing the steam to pass to the inspirator or injector, thereby starting the overflow, which, pressing on the piston k in vessel i, pulls the lever l of the inspirator down, thereby closing the overflow-valve. The water then passes into the pipe g and to the boiler, lifting the valve m, which depresses the end of the lever n next to the piston-rod k.

On the end of the lever n is a pawl, n', which engages teeth on the rod, so that when the current of water breaks the steam-pressure on

valve m forces the valve down, and by the lever n the piston k and rod k' are lifted, and this at the same time lifts the lever l and the pawl n' is tripped, leaving the piston k free 5 to be acted upon again by the overflow.

Having thus fully described my invention, I claim as new and desire to secure by Letters Patent—

1. In a boiler feed-water apparatus, the combination, with the boiler, the steam-regulator, and the feed-water pipe, of the injector or inspirator having an overflow-outlet, with its valve adapted to be closed by the action of the overflow water after leaving the overflow-out- 10 let to cause the feeding of the water to the boiler, substantially as set forth.

2. In a boiler feed-water apparatus, the combination, with the boiler, the steam-regulator, and the feed-water pipe, of the injector or inspirator having an overflow-outlet, with its valve connected to a piston-rod, also connected to a valve in the feed-water pipe, the piston being acted upon by the overflow water, sub- 20 stantially as and for the purpose set forth.

3. The relief-valve a , combined with the regulator, and fitted for operation by the main valves, substantially as described. 25

4. The regulator-valves F , of the form shown, and the double valve a , combined for operation as specified. 30

5. The combination of the injector D , the overflow h , the vessel i , levers n l , and valve m , substantially as described, for operation in the manner specified.

6. The combination of the injector D , over- 35 flow h , vessel i , levers l n , piston k and its rod k' , pipe g , and valve m , substantially as and for the purpose set forth.

7. The combination of the injector D , over- 40 flow h , vessel i , levers l n , the latter having the pawl n' , piston k and its rod k' , pipe g , and valve m , substantially as and for the purpose set forth.

JOHN S. CLARKE.
